STRIP DISPENSER

Stevenson White, Owings Mills, Md.

Application May 1, 1948, Serial No. 146,109

Term of patent 14 years

(Cl. D74—1)

To all whom it may concern:

Be it known that I, Stevenson White, a citizen of the United States of America, residing at Owings Mills, in the county of Baltimore and State of Maryland, have invented a new, original, and ornamental Design for a Strip Dispenser, of which the following is a specification, reference being had to the accompanying drawings, forming part thereof.

Figure 1 is a side view of a strip dispenser, showing my new design.

Figure 2 is an end view of the same.

Figure 3 is a perspective view of the dispenser.

Figure 4 is a plan view of the same.

Figure 5 is a bottom plan view of the same.

I claim:

The ornamental design for a strip dispenser, substantially as shown.

STEVENSON WHITE.
